CLAIM

The ornamental design for a blower unit as shown and described.

DESCRIPTION

FIG. 1 is a front elevational view of a blower unit in accordance with my new design;

FIG. 2 is a left side elevational view thereof;

FIG. 3 is a right side elevational view thereof;

FIG. 4 is a top plan view thereof;

FIG. 5 is a rear elevational view thereof; and,

FIG. 6 is a front and left side perspective view thereof.

The bottom view of the blower unit is not shown in the drawings or described in the specification and, therefore, forms no part of the claimed design. Broken lines illustrate portions of the blower unit that form no part of the claimed design.
